UNITED STATES PATENT OFFICE.

SAMUEL B. McHENRY, OF BLOOMSBURG, PENNSYLVANIA.

BROOM.

Application filed August 17, 1923, Serial No. 657,964. Renewed September 21, 1927.

This invention relates to improvements in brooms, the general object of the invention being to provide novel means of connecting the bristles with the handle so that new bristles can be easily attached to the handle when the old ones have become worn.

Another object of the invention is to provide simple means for connecting the bristle carrying part with the handle.

10 A further object of the invention is to provide means for firmly binding the bristles together, in looped form, so that they will be held in a compact mass.

This invention also consists in certain 15 other features of construction and in the combination and arrangement of the several parts, to be hereinafter fully described, illustrated in the accompanying drawings and specifically pointed out in the appended 20 claim.

In describing my invention in detail, reference will be had to the accompanying drawings wherein like characters denote like or corresponding parts throughout the several views, and in which:

25 Figure 1 is an elevation of the invention.

Figure 2 is a sectional view through the same.

In the form shown in Figures 1 and 2, the 30 holding member 4 is extended to form a handle 1 and the band 9 is located high so as to engage the shoulders of the broom head and the upper portions of the loops of the member 4. The arrangement of the bands in 35 the forms shown in the figures will prevent

turning movement of the broom head on the handle.

In all the forms where a wooden handle is used I prefer to groove the handles to receive the limbs of the U-shaped portion of 40 the connecting device.

From the foregoing it will be seen that I have provided simple means for fastening the bristles to the handle so that the broom or brush can be manufactured to sell at low 45 cost and the connecting means are so formed that new bristles can be easily and quickly placed in position after the old ones have become worn and removed.

It is thought from the foregoing description that the advantages and novel features of my invention will be readily apparent.

I desire it to be understood that I may make changes in the construction and in the combination and arrangement of the several 55 parts, provided that such changes fall within the scope of the appended claim.

What I claim is:—

A broom of the class described, comprising a broom head formed of a body of straw 60 folded upon itself, a band passing around the bight portion, a handle having a looped lower end which engages the bight portion of the broom head, a band passing around the folded part of the head, and pins passing through the band, the folded part of the head, through the loops of the handle and through the first band.

In testimony whereof I affix my signature.

SAMUEL B. McHENRY.
